ALEXANDER NYMAN, OF EAST ORANGE, NEW JERSEY, ASSIGNOR TO WESTINGHOUSE ELECTRIC & MANUFACTURING COMPANY, A CORPORATION OF PENNSYLVANIA.

MICROPHONE.

Application filed March 1, 1924. Serial No. 696,177.

This invention relates to microphones, particularly to microphones of the type used in connection with radio broad-casting.

It is an object of this invention to provide a microphone which shall be of great sensitivity, well protected from mechanical vibration and as free as possible from resonance periods inherent in the instrument.

It is a further object of this invention to surround the microphone unit with sound-filtering means which shall permit sounds of low pitch to reach the microphone but shall prevent the sounds of high pitch from reaching the instrument, except over a predetermined path.

It is a further object of the invention to protect the microphone from such damage as might be caused by rough handling.

It is a further object of this invention to provide a microphone of materials which are non-resonant so that vibration of the materials out of which the microphone is constructed shall not produce undesired results.

It is a further object of this invention to use sonorous material for certain parts of the instrument in order to reinforce the vibrations of higher frequency.

It is a further object of this invention to provide a microphone diaphragm as free as possible from tendency to vibrate at its own natural period. Incidentally, the invention includes an expedient by which non-conducting materials may be used in a microphone of the type in which electric currents are conducted by the diaphragm.

A further object of this invention is to prevent the cavities within the microphone case from acting as resonators.

It is a further object of this invention to support the microphone in such manner that it shall receive no impulses except those due to sound, all other mechanical jars being excluded.

It is a further object of this invention to provide a means for clamping the diaphragm at its edges in such way that no distortion of the diaphragm, which might cause it to vibrate more at certain periods than at others, shall be introduced by the clamping action.

It is a further object of this invention to provide an electrical connection to both faces of the diaphragm at the edge thereof without defeating the object just stated.

Other objects of the invention and details

of the construction will be apparent from the following description and accompanying drawings in which:

Figure 1 is a longitudinal sectional view of the diaphragm and its housing, 60

Fig. 2 is a sectional view at right angles to Fig. 1, showing the diaphragm unit and a portion of the housing, other parts being omitted,

Fig. 3 is a diagrammatic view of the electrical connections, 65

Fig. 4 is a radial sectional view through the clamping means and the edge of the diaphragm,

Fig. 5 is an elevational view of a modified supporting means, and 70

Fig. 6 is a rear view of the microphone of Fig. 5.

The microphone is supplied with a diaphragm 10 which consists of a disc 11 of thin cardboard, upon each face of which is a strip 12 of gold leaf. Cardboard has been chosen because of its lack of tendency to maintain vibrations after being distorted. This characteristic of cardboard, in my opinion, is 75 partly the result of internal frictional forces developed when the diaphragm is distorted. Many other materials may be used, such as hard carbon, mica, celluloid, micarta and fullerboard, but cardboard gives the best results of the materials that I have tested. 80

Most conveniently, these strips of gold leaf are made in one continuous piece around the edges of the diaphragm, but two strips, one for each face, may be used if desired. The 90 gold leaf is secured to the cardboard disc by an adhesive. An aqueous solution of the adhesive must not be used because the water would cause the cardboard disc to warp. Preferably, an alcoholic solution of shellac 95 is employed.

In order to make electrical connection with the gold leaf on both faces of the cardboard, a conductor 13, best shown in Fig. 4, is provided, which extends around the edge 100 of the diaphragm 11 into contact with the gold leaf on each face thereof. The conductor 13 must be very small and flexible. Preferably, a very fine grade of braided conductor, such as is used in selector switches in 105 automatic telephony, is employed, but a single strand of ordinary telephone cord will serve well. At one end, the conductor 13 is soldered, or otherwise connected, to a terminal piece 14 which is attached by a screw, or 110

by any other desired fastening, to a hard rubber ring 15.

The ring 15 is one of a pair of rings 15 and 16 which surround the diaphragm 10. The rings 15 and 16 are of hard rubber because that material is comparatively free from "ring". That is to say, it is non-sonorous, in that it does not produce a sustained note when struck. For this reason, any tendency of the rings 15 and 16 to vibrate and so set the diaphragm into vibration at a particular period is avoided. The rings are of slightly larger diameter than the diaphragm in order that the edge of the diaphragm shall not engage the interior wall of the rings. Any possibility that the rings, by crowding the diaphragm, might cause it to buckle is thus avoided. If any distortion is introduced in the diaphragm, either by the rings crowding it or by the clamping action described below being unevenly distributed, there will result a tendency for the diaphragm to vibrate more readily at certain periods than at others and "blasting" or reinforcement of particular high notes will be caused.

The inner walls of the rings 15 and 16 have shoulders, to provide a recess, into which the diaphragm extends. Seated in this recess are soft rubber washers 17. Preferably, there are two of these washers on one side of the diaphragm and one on the other, but any number of washers distributed in any desired way, may be employed. There must, however, be, at least, one soft rubber washer on each side of the diaphragm in order that it shall be cushioned on both sides.

The washers are of flat sheet material. Soft rubber tubes or cords have been found to cause a tendency of the diaphragm to take an arched shape and "blasting" results. Also, such members of circular cross section lose their effectiveness as the rubber ages. The combined thickness of the washers and diaphragm should, when the washers are in their uncomplicated condition, slightly exceed the height of the recess. This excess should only be slight because, when the rings 15 and 16 are brought together, the pressure upon the diaphragm should be small. If the soft rubber washers are not of proper dimensions, to readily accomplish this, the combined thickness may be brought to the desired size by introducing one or more washers of thin paper.

The hard rubber rings are secured together by a plurality of screws 21, six being shown by way of example, in Fig. 2. A smaller number is disadvantageous because it is difficult to distribute the pressure with sufficient uniformity unless the number of screws be large. A greater number than six may be used, if desired. By suitably adjusting each of the screws 21, the pressure of the washers 17 against the diaphragm may be made uniform throughout the whole circumference.

65 The conductor 13 is so small that the extra

compression of the washers caused by it is not sufficient to produce any perceptible difference in the distribution of the pressure upon the diaphragm. The flat shape of each strand in a cable, or of the single strand, if 70 a single one be used, is an additional reason why no appreciable excess of pressure upon the washers and diaphragm is caused by the wire.

A cup 22, preferably of brass, holds a body 75 23 of carbon granules. The edge of this cup is faced with a felt washer 24 which contacts with the diaphragm. The contact is sufficiently close to prevent the escape of the carbon granules 23. At the same time, it is 80 sufficiently light to permit vibration of the diaphragm 10. During such vibration, however, the diaphragm compresses the felt slightly. Since the felt is more readily compressed than the body of carbon granules, 85 the magnitude of pressure changes in that body caused by the motion of the diaphragm is not diminished by the presence of the felt. The felt, however, assists in damping out vibrations, consequently, if there be any tendency of the diaphragm to vibrate at its own natural period, it is diminished by the felt.

The bottom of the cup 22 is covered by a disc 25 of metal having a facing of carbon soldered thereto. This disc is secured in place by a screw 26 integral therewith and extending through the bottom of the cup. The screw is received in a cylindrical holder 27 by means of which the cup is secured in position in a hub 28. A slot 29, suitable for the reception of a screw-driver, facilitates adjustment of the position of the cup.

95 By giving the holder 27 a rotary movement with a screw driver, the position of the holder in the hub may be adjusted lengthwise with greater nicety than if no rotation of the holder were possible. The slot 29 is also a convenience when the cup 22, false bottom 25 and holder 27 are being assembled. A set screw 31, through the wall of hub 28, serves to hold 100 the cup in position.

105 The hub 28 is supported upon a bridge 32 which extends diametrically across the ring 16 and is secured thereto at each end by screws 33. This bridge is made of brass. 115 Bridges of hard rubber have been tried but the advantage gained thereby is very slight. Moreover, it is quite possible that the ringing or resounding quality of the brass reinforces vibrations at certain very high pitches, at 120 which such reinforcement is desirable. A terminal screw 34 mounted upon the bridge 32, facilitates the attachment of a conductor 35 which extends to the outside of the instrument. For convenience in assembling, holes 125 are provided in the rings 15 and 16 through which the conductor 35 is passed.

130 Upon the opposite side of the diaphragm, a similar bridge 42 is mounted, which carries a cup 43 holding a body 45 of carbon granules.

The cup 43 is of slightly greater diameter than the cup 22 so that the felt washer 44 upon the cup 43 contacts with the diaphragm over an annular area just outside of that contacted by the felt washer 24. The conductor 46 is secured to the bridge 42 in a way similar to that used to secure the conductor 35 to the bridge 32 and it also extends to the outside of the instrument. A third conductor 50 extends from the outside of the instrument to the terminal 14 secured on the ring 15.

The ring 16 is provided with a bead 51 which serves as an abutment for a cover 52 extending over the front of the microphone. The central part of this cover is open and, to protect the instrument, the opening is occupied by an arched screen 53.

Between the screen 53 and the diaphragm 10 is a space which, if not modified, could act like a short organ pipe and thus provide resonance for certain high-pitched sounds. This action would result in sufficient "blasting" to seriously interfere with the reproduction of music. To avoid this difficulty, the cylindrical wall of the cover has a felt lining 54. The action of this lining, by absorbing sound energy, prevents the space between the screen 53 and the diaphragm from acting as a resonator.

The rear of the microphone is closed by a cover 55 of any convenient shape. The bead 51 acts as a stop for this cover also. An opening 56 is provided in this cover, through which the conductors 35, 46 and 50 emerge.

The microphone unit, the cover enclosing it and the conductors, are housed within an enclosure comprising a tube 60 of any convenient material. Micarta has been found to serve well. At the rear, the enclosure includes a disc 61, also of micarta, although many other materials will serve. A reinforcing strip 62 is provided at that part of the sleeve 60 where the conductors 35, 46 and 50 emerge and binding posts 63, 64 and 65, one for each conductor, are mounted on the reinforcing strip.

The space between the micarta enclosure and the microphone casing is filled with felt. The felt used is sufficiently hard to support the microphone in place within the enclosure and protects it from injury by rough handling. It is sufficiently loose in its texture to afford a damping action upon all sounds except those of very low pitch. The interstices between the fibres of felt are small enough so that none of them can constitute a resonance chamber for sound vibrations, the pitch of which is within the limit of audition. Care must be taken in cutting and fitting the various pieces of felt, that no cavities are left which can form such resonance chambers. The damping action of the felt assists, however, in preventing resonance in such cavities as are present.

The front layer 67 of felt is a ring sur-

rounding the screen 53. The opening 68 in this ring constitutes a channel through which sound can reach the microphone. The layers of felt immediately at the rear of the microphone are so cut as to provide a channel 70 through which the conductors 35, 46 and 50 may reach the binding posts 63, 64 and 65.

In order to support the instrument, two bands 70 of metal are placed around the two ends of the sleeve and each band is secured by a bolt 71. One end of each band is made to project upward beyond the bolt and has a hole 72. The holes serve as attaching means for strips 73, of extensible rubber or other flexible material which form a suspensory device. The upper ends of the rubber strips are secured to any desired support. It has been found that helical springs or other metal suspensory devices do not serve well for hanging the microphone, because they possess a resounding quality and produce a ring which gives rise to a noticeable "blast".

The microphone is connected to the radio sending apparatus by means of the circuit illustrated in Fig. 3, in which the battery 75 feeds the potentiometer 76. One end of this potentiometer is connected to the terminal 14 and thereby to the gold leaf upon the diaphragm. The other side of the potentiometer is connected to the middle point of an inductor 77, which forms the primary winding of a transformer, the secondary winding 78 of which is connected to the amplifier or other suitable element of the radio system. The two terminals of the inductor 77 are connected to the two cups 22 and 43 by means of the conductors 35 and 46, the bridges 32 and 42 and the cup holders. In shunt to the inductor 77 is an adjustable resistor 79 of greater resistance than the microphone. This resistor serves to give added steadiness to the signals transmitted.

The microphone when associated with the enclosure described, is particularly suitable for transmitting music. When speech is to be transmitted it is desirable to use, instead of the rear cover 55, a rear cover provided with a screen 81 (Fig. 6) similar to the screen 53 except that it has an opening for the conductors.

Obviously, such a microphone cannot be used in the enclosure 60, because the opening at the rear thereof would be useless. It is, therefore, mounted in a ring 82 supported on a standard 83 similar to the usual desk-telephone stand. The ring 82 is provided with a number of hooks 84 through each of which extends a rubber suspensory device 85. This device may consist of one or more extensible rubber bands for each hook, or a single extensible rubber band may be used, passing through all of the hooks. The microphone is supplied with a number of projecting attachment devices 86, preferably fastened to the micro-

phone by putting screws into holes 87 in the bead 51. The suspensory device 85 is made to pass around each of the projections 86 and so holds the microphone in place within 5 the ring. The conductors 35, 46 and 50 extend from the microphone into the interior of the standard 83 and out at the base 88 in the same way as an ordinary telephone cord.

When the user speaks into the microphone 10 shown in Fig. 5, there is no reflection of his voice from the rear of the casing or of the enclosure because both of these have open rear faces. Consequently, resonance due to 15 the space between the diaphragm and the rear face is avoided. The enclosure and support illustrated in Fig. 1 afford protection from extraneous noises and a selective reception of 20 very low tones. These properties are of great advantage when transmitting music but are not so important when transmitting speech.

Although I have illustrated and specifically 25 described but one form on my microphone unit and but two forms of enclosure and support therefor, many variations in the details 30 of the structure will be obvious to those skilled in the art and I do not intend the specific disclosure made to be considered as a limitation.

I claim as my invention:

30 1. In a microphone, a body of loose grains of carbon, a cup for holding said body, a felt rim secured to said cup and surrounding the mouth thereof, a diaphragm engaging said rim, and means for adjusting the 35 cup toward and from the diaphragm to regulate the damping action of said felt rim.

2. In a microphone, a diaphragm, two granule cups, one on each side thereof concentric therewith and of different diameters and damping means coextensive with the 40 cups.

3. In a microphone, a diaphragm, two granule cups, one on each side thereof concentric therewith and of different diameters, damping means on the edge of each cup, the 45 outer edge of the smaller damping means being approximately opposite the inner edge of the large damping means.

4. In a microphone, a diaphragm, annular damping means contacting the diaphragm on 50 each face, one of said means being of larger diameter than the other.

5. A diaphragm for microphones comprising a plate of cardboard having a coating of gold foil secured to each face thereof by non-aqueous adhesive. 55

6. In a sound-responsive device, a microphone unit, a casing housing said unit and having a sound-receptive opening, an enclosure surrounding said casing and having 60 an opening in alignment with said sound-receptive opening, a packing of material which prevents the passage of high-pitched sounds, said packing filling said enclosure external of said casing, and an opening through 65 said packing, extending from said opening in the enclosure to said sound receptive opening.

In testimony whereof, I have hereunto subscribed my name this 18th day of February, 70 1924.

ALEXANDER NYMAN.
